ARCHIE REXALD WOLFE, OF SUMMIT, NEW JERSEY.

MULTIPOLE MULTIBRANCH ELECTRIC SWITCH.

Application filed April 3, 1925. Serial No. 20,541.

My invention relates to improvements in multipole multibranch switches of the low loss blade and receptacle type, having either stationary main distributing pole blades and 5 movable branch pole receptacles, or stationary main distributing pole receptacles and movable branch pole blades. This switch described and illustrated in this specification is of the former type.

10 The objects of my improvement are, first, to provide a means of directly and quickly connecting the leads from one aerial or loop, one ground connection, one source of plate current, one source of filament current and 15 one loud speaker as may be required to any one of three or more (the larger number depending upon the design of the switch) radio or radiophone receiving sets as desired for demonstration or other purposes, and at the 20 same time have no dead end or noncurrent carrying conductors connected to the circuits, and have the leads connecting said sources of current to the receiving set of practically the same length regardless as to which one 25 of the three or more receiving sets are so connected. (The latter is accomplished in connection with the use of the multipole multibranch switch by having the receiving sets located equidistant radially from the said 30 switch); second, to provide for individual operation of any one of the branch ways of the switch, by local control, or by extended control from a point within four feet of the switch and near on a line with the top center of the 35 pedestal shaft and said branch way; third, to provide a type of multipole multibranch switch which can be readily designed for voltages in general use, and to most efficiently distribute from a central supply of current or 40 currents requiring any number of poles to any number of branches or points of the compass; fourth, to provide a multipole multi-branch switch of such construction that it can readily be provided with a metal cover, render- 45 ing the switch practically dust proof without interfering with its operation.

The apparatus and mechanism of one form of the invention, a seventeen pole eight branch electric switch is illustrated in the accom- 50 panying drawings, in which Fig. 1 is an approximate full size vertical section of the

switch on the broken line 1 1, Fig. 2, with the branch binding post bars 28, branch binding posts 29 and insulated flexible leads 30 omitted; Fig. 2 is a view looking down on the 55 top of the entire switch with cover removed, and with the base and lower portion proportionately enlarged and brought into view; Fig. 3 is a view of a part of the switch showing one end of one of the adjustable support- 60 ing guides 14; Fig. 4 is a cross section view of the shaft bushing 7, and a view in perspective of one main distributing pole 8 in place on said bushing. Similar numerals refer to 65 similar parts throughout the several views.

The pedestal shaft 1 rigidly supports the metal top plate 4, between the nuts 5 and 6, and is rigidly secured to the supporting base 2, to which 3 the metal bottom plate, is secured by machine screws. 7 a cylindrical 70 bushing of insulating material, fits snugly over shaft 1 covering nearly its entire length, and is rigidly secured to it by counter sunk machine screws. The washer shaped blades 75 8 are the main distributing poles of the switch. They fit over the bushing 7, and are provided with a permanent key 9, which fits into keyway 10, on the bushing 7, preventing them from turning when in place.

11 are bushings of insulating material 80 which fit over bushing 7, and serve to support and separate the main distributing poles 8, and by screwing up on nut 6 pressure is brought to bear on the entire column of bushings 11, and main distributing poles 8, thus 85 holding the latter rigidly in place. The plates 3 and 4 have an equal number of equally spaced rectangular slots 12, in which travel the guiding shoulders 13, of the adjustable metal supporting guides 14, one of 90 which support and guide each end of each branch pole bar 15, which are made of insulating material and to which the spring copper or brass receptacle contacts 16, which are 95 the branch poles of the switch, are secured. A second pair of shoulders 17, on each adjustable supporting guide 14, forms their sliding support which bears on a portion of the upper surface of bottom plate 3 or under surface of top plate 4 as the case may be.

100 One adjustable supporting guide 14 is clamped over each end of each branch pole

bar 15 by means of tightening the nuts of bolts 18, or by loosening the nuts, the vertical position of each branch pole bar 15, and its supporting guides 14, may be varied a distance limited by the length of the slots 19, in the latter.

To each end of the metal control rods 20, which pass through bearing holes in the plates 3 and 4 is secured a cam lever 21, having a rectangular slot which fits over the projecting stud 22, of the adjustable supporting guides 14.

It can readily be seen that as the two cam levers at ends of any one control rod 20 are placed over the stud 22 and secured to said control rod in a position parallel to each other, each branch pole bar 15 will at all times be parallel to the pedestal shaft 1, and a partial revolution of said control rod in its bearings will move the branch poles 16 into contact, or out of contact, with their respective main distributing poles 8 as may be desired, and the springs 31 tend to maintain those positions.

Referring to Fig. 2 it will be noticed that one of the branch pole bars are closed. In this position the branch pole receptacles 16, close over the main distributing pole blades 8, making contact for a distance of one fourth of an inch.

The rotating movement of the control rod 20 is effected either by direct control by means of the insulated handles 23, which are secured to the control rods 20 by set screw and as shown in Fig. 2, or by extended control, by means of extension rods connected to the stud bearing pins 24, on the cams 21.

Each branch pole bar 15, together with its respective equipment required for its proper operation and connection, constitutes a branch way of the switch.

Each main distributing pole 8 has an individual insulated wire 25, shown by the broken parallel lines in Fig. 2, soldered to it and connecting it with a respective binding post 26, on the main binding post bar 27, which is made of insulated material and is secured to a projection of the top plate 4, shown in Fig. 2, and to the base 2 by machine screws. On this bar 27 are mounted seventeen binding posts or one for each pole of the switch, to which, leads from the sources of current or currents to be distributed should ordinarily be connected. I desire to state here that it is not absolutely necessary to so connect the supply leads from the sources of current or currents to be distributed in order to operate the switch, instead, they may be connected to the binding posts 29, of any one branch way not in use, and the branch way to which connected will then serve as the main feed switch, or cut out switch, as desired, for all of said supply leads.

The branch binding post bars 28, are made of insulating material and are secured by ma-

chine screws to projections of the top plate 4 and to the base 2 in a position parallel to the shaft 1, and to each other. On each of the branch binding post bars are mounted the branch binding posts 29, there being one binding post for each pole the switch is designed for, or in this case seventeen, each one of which is connected to a respective branch pole 16, by one of the insulated flexible leads 30.

Reference to Figs. 1, 2 and 3 will show that a smaller central portion projects from the rear of each binding post 26 and 29 and each branch post 16, so that leads may be soldered to them without impairing the threads.

The entire switch, when installed, can be secured for operation by screws through the holes 32, in base 2, shown in Fig. 2.

I am aware that multipole double throw or two branch switches, having knife blade main distributing poles which can be thrown into contact with respective branch pole receptacles of either one of two branch ways, have been in general use prior to my invention, and I do not claim such a switch; but

I claim:

1. In a multipole multibranch electric switch comprising a central column of distributing poles insulated from each other, distributor terminals therefor, a plurality of columns of receptor contacts insulated from each other, arranged radially about said central column, receptor terminals therefor, and means whereby any number of columns of receptor contacts may be moved radially with respect to said central column to complete the circuit between said receptor and distributor terminals.

2. In a multipole multibranch electric switch, a central column of poles insulated from each other and spaced apart a predetermined distance, a plurality of columns of similarly arranged contacts disposed around said central column and means whereby the radially disposed columns are moved to make contact with said central column of poles.

3. In a multipole multibranch electric switch, a central column of poles insulated from each other and spaced apart a predetermined distance, a plurality of columns of similarly arranged contacts disposed around said central column and means whereby the radially disposed columns are moved radially to make contact with said central column of poles.

4. In a multipole multibranch electric switch, a central column of poles insulated from each other and spaced apart a predetermined distance, a plurality of columns of similarly arranged contacts disposed around said central column at equal angles and means whereby the radially disposed columns are moved radially to make contact with said central column of poles.

5. In a multipole multibranch switch, com-

prising a base, an end plate mounted on said base, a central vertical support mounted on said base, alternate washer shaped conducting blades and insulating bushings surrounding

5 said support, a second face plate, a plurality of columns of receptor contacts radially arranged about said center column and mount-

ed between said face plates, terminals therefor, and means whereby any number of said columns of receptor contacts are moved radially to make contact with said distributing column.

10

ARCHIE REXALD WOLFE.
